F. P. MURDOCH.
HANGER FOR RADIATORS.
APPLICATION FILED MAY 3, 1919.

Patented Aug. 5, 1919.

1,311,908.

Inventor:
Franklin P. Murdoch,
by his attorney,
Charles R. Searle.

UNITED STATES PATENT OFFICE.

FRANKLIN P. MURDOCH, OF EAST ORANGE, NEW JERSEY, ASSIGNOR TO GILLIS & GEOGHEGAN, OF NEW YORK, N. Y., A FIRM.

HANGER FOR RADIATORS.

1,311,908.

Specification of Letters Patent.

Patented Aug. 5, 1919.

Application filed May 3, 1919. Serial No. 294,453.

To all whom it may concern:

Be it known that I, FRANKLIN P. MURDOCH, a citizen of the United States, residing at East Orange, in the county of Essex and 5 State of New Jersey, have invented a certain new and useful Improvement in Hangers for Radiators, of which the following is a specification.

The invention relates to devices for supporting heating radiators upon the wall, and the object of the invention is to provide a simple, inexpensive hanger in one piece, which supports the radiator reliably, is easily secured to the wall, and is practically 15 concealed from view when the radiator is in position thereon.

The invention consists in certain novel details of construction and arrangement by which the above objects are attained, to be 20 hereinafter described and claimed.

The accompanying drawings form a part of this specification and show the invention as it has been carried out in practice.

Figure 1 is an end view of a radiator supported on one of the improved hangers.

Fig. 2 is a corresponding front elevation.

The remaining figures are on a larger scale and show the hanger alone.

Fig. 3 is a front view of the hanger.

Fig. 4 is a plan view of the same.

Fig. 5 is a corresponding end view.

Fig. 6 is a vertical transverse section taken on the line 6—6 in Fig. 3, and partly in elevation.

Similar letters of reference indicate the same parts in all the figures.

A is a radiator, shown as composed of a series of cast sections joined at their upper and lower ends by connected bosses A¹ and 40 A² formed on their adjacent faces. The radiator may be understood to be of any approved type, adapted for steam or hot water heating systems, and equipped with the usual pipes, valves, and connections, not 45 shown.

The hanger comprises a strip or narrow plate B of heavy sheet metal having its ends bent outwardly at a right angle, parallel with each other to form brackets B¹ B¹ on 50 which the radiator is hung. The brackets are each provided with a curved notch b on the upper edge, adapted to extend between adjacent sections and match approximately

to and receive the lower faces of the upper bosses A¹ of the radiator, or other like connections.

The body B has a longitudinally extending slot b¹ near each end adapted to receive a fastening means for securing the hanger to the wall, which may be a simple stud-bolt, 60 as at C in Fig. 1, or an expansion bolt or a yoke with threaded ends to extend through the slots and receive nuts, depending upon the character of the wall to which the radiator is to be attached. The slots b¹ offer a 65 degree of longitudinal adjustment in locating the hanger relatively to the spaces between the sections of the radiator.

In applying the hanger it is so located as to present its brackets B¹ in position to 70 extend each into the space between two adjacent sections of the radiator at separated points on the latter and preferably positioned about centrally thereof. The hanger is then secured to the wall and the radiator 75 placed thereon with its bosses A¹ engaged in the notches b b of the brackets.

The under face of each bracket is cut away, as at B², and presents but little outward face so that when the radiator is in 80 place with the brackets in the narrow spaces between the sections, the holder is so inconspicuous as to be practically invisible.

By making the holder in a single piece only two bolts are required to support the 85 radiator reliably and these are easily located, and sufficient adjustment is permitted by the slots b¹ to allow for slight variations in position.

I claim:—

The holder described comprising a single plate of sheet metal bent at each end to form outwardly extended parallel brackets, and having longitudinally disposed slots adapted to receive bolts for the attachment 95 of said plate to a wall, said brackets having their upper edges in the form of notches and adapted to project into the spaces between adjacent sections of a radiator at separated points in the latter, said notches adapted to 100 receive the bosses of said sections and thereby support such radiator.

In testimony that I claim the invention above set forth I affix my signature.

FRANKLIN P. MURDOCH.
